UNITED STATES PATENT OFFICE.

OSWALD LECQUOETTE FILLMORE, OF HARRIMAN, TENNESSEE.

VALVE.

Application filed November 3, 1922. Serial No. 598,938.

To all whom it may concern:

Be it known that I, OSWALD L. FILLMORE, a citizen of the United States, residing at Harriman, in the county of Roane and State of Tennessee, have invented new and useful Improvements in Valves, of which the following is a specification.

This invention relates to a gasoline supply station, the general object of the invention being to provide compressed air for forcing the gasoline from the supply tank to the transparent chamber of the pedestal.

Another object of the invention is to provide a single valve for controlling the flow of gasoline into the said chamber and the passage of the surplus gasoline from the said chamber back to the supply tank as well as to control the flow of air.

Another object of the invention is to provide an auxiliary tank which is kept filled from the main tank under the action of gravity and to which the air supply is connected.

This invention also consists in certain other features of construction and in the combination and arrangement of the several parts, to be hereinafter fully described, illustrated in the accompanying drawings, and specifically pointed out in the appended claim.

In describing my invention in detail, reference will be had to the accompanying drawings wherein like characters denote like or corresponding parts throughout the several views, and in which:—

Figure 1 is a diagrammatic view of the system.

Figure 2 is a plan view of the valve.

Figure 3 is a bottom plan view with the connecting pipes in section.

Figure 4 is a top plan view with the cover removed.

Figure 5 is a longitudinal sectional view through the valve.

In these views 1 indicates the supply tank, 2 the auxiliary tank which is connected by the pipe 3 with the main tank in such a manner that it will be kept filled with gasoline under the action of gravity. A check valve 4 is arranged in the pipe 3. The pedestal is shown at 5 and said pedestal is preferably provided with the chamber 6, the walls of which are formed of transparent material. A valve casing 7 is arranged in the base of the pedestal and a pipe 8 has one end connected with the top of said

casing and the top of this pipe is located in the chamber 6. A pipe 9 connects the bottom of the casing with the auxiliary tank 2 and a pipe 10 connects the bottom of the casing with the main tank 1. An air pipe 11 connects the bottom of the casing with the auxiliary tank 2 and a pipe 12 connects the bottom of the casing with a tank 13 which contains a supply of compressed air. 60 14 indicates a vent pipe which is connected with the bottom of the casing. A valve disc 15 is arranged in the casing and is ground to make a tight fit with the bottom thereof. The valve disc is held on its seat by a spring 16. The stem 17 of the valve disc passes through the top of the casing and is connected with a handle 18. The disc is provided with a port 19 which passes entirely through the disc and with passages 20 and 21 which are arranged in the lower face of the disc. A valve 22 is arranged in the pipe 12 and the parts of this valve are so arranged that it will be operated by the handle 18 when said handle is moved in one direction. Stops 22' are located on the top of the casing for limiting the movement of the handle. 70 75 80

When the chamber 6 is to be filled with gasoline the handle 18 is moved to the left 85 in Figure 2 so as to place the port 19 in the disc valve over the pipe 9 and to place the passage 21 in a position to connect the pipes 12 and 11. This movement of the handle will also open valve 22. Thus air will flow 90 from the tank 13 through the pipe 12, across the passage 21 and through the pipe 11 into the tank 2. This compressed air will force the gasoline from the tank 2 through the pipe 9, into the valve casing through the 95 port 19 and from the casing the gasoline will pass through the pipe 8 into the chamber 6. When the chamber is filled the handle is moved to its first position so as to place the port 19 over the pipe 10 so that 100 the surplus gasoline in the chamber 6 can flow back into the tank 1. This surplus gasoline will flow back through the pipe 8 into the valve casing through the port 19 and through the pipe 10 and thus return to the 105 tank 1. At the same time the passage 20 is placed in position to connect the pipe 11 with the vent pipe 14 so that the air in the auxiliary tank 2 can escape and thus permit the tank to be refilled from the main 110 tank. The valve 22 will close as soon as it is disengaged by the handle.

From the above it will be seen that the disc valve 15 controls the passage of air into the auxiliary tank and the escape of this air therefrom and it also controls the 5 flow of gasoline from the auxiliary tank into the chamber 6 and the return of the surplus gasoline in chamber 6 to the main tank.

It is thought from the foregoing description that the advantages and novel features 10 of my invention will be readily apparent.

I desire it to be understood that I may make changes in the construction and in the combination and arrangement of the several 15 parts, provided that such changes fall within the scope of the appended claim.

What I claim is:—

An apparatus of the class described comprising a main tank, an auxiliary tank arranged 20 to be filled from the main tank under the action of gravity, a delivery cham-

ber, a valve casing, a pipe connecting the same with the upper part of the delivery chamber, a pipe connecting the casing with the auxiliary tank, a pipe connecting the casing with the main tank, an air tank, a pipe connecting the same with the valve casing, an air pipe connecting the valve casing with the auxiliary tank, a vent pipe connected with the valve casing, a valve in 25 the casing having a port therein for connecting the delivery pipe with either the pipe leading to the auxiliary tank or with the main tank and also having passages therein for connecting the air tank with the auxiliary tank or the auxiliary tank with the vent pipe, a handle for operating the valve and a valve for controlling the flow of air from the air tank into the casing, said valve being operated by the handle.

In testimony whereof I affix my signature.

OSWALD LECQUETTE FILMORE.
